UNITED STATES PATENT OFFICE.

WILLIAM T. SHERER, OF CHICAGO, ILLINOIS.

DISPLAY CASE.

Application filed June 20, 1925. Serial No 38,479.

My invention relates to an improvement in display cases, for example to a case of the type wherein a plurality of separate compartments are provided with slide gates 5 positioned to the rear of the case. One object of my invention is to provide a case into which access may be had into a plurality of such compartments at the same time. Other objects will appear from time to time 10 in the course of the specification and claims.

I illustrate my invention more or less diagrammatically in the accompanying drawings wherein—

Figure 1 is an elevation; 15 Figure 2 is a horizontal section; and Figure 3 is a partial plan view of the bottom member of the case.

Like parts are illustrated by like symbols throughout the specification and drawings. 20 Referring to the drawings, A A¹ are any suitable end panels or members, which may be provided, if desired, with glass or other translucent material.

B B¹ and B² are the transparent front 25 panels of the case.

C is any suitable base, and C¹ any suitable top member.

The case is divided into a plurality of 30 separate compartments, herein shown as three, for example by the partitions D and D¹. Since it is preferred, in the use of my cases, for example, for bakery purposes, to prevent the passage of air from one compartment to another, I may provide any 35 suitable felting or packing D² D³ at the inner ends of such compartments, in order to make a tight connection with doors below described. Any suitable material may be used, but I find a relatively thin layer or 40 cushion of felt to provide a sufficiently tight connection.

It will be noted that the end panels A A¹ are of the same length, that the partition D¹ is somewhat shorter than the end panels and 45 that the partition D is shorter than the panel D¹.

E is a track extending from the end panel A to the partition D¹ and riding upon them is the sliding gate E¹. Its normal position 50 for closure is at the left extremity of the track when it closes the compartment formed by the end panel A and the partition D. It is provided with a felting E² at one end, and the felting E³ at the other, to

make a tight fitting closure. D² is felting 55 at the outer edge of the partition D.

G is a second track extending from the partition A to the partition D¹ and upon it rides a similar sliding gate G¹. Its range of excursion, like that of the gate E¹ is limited 60 on one end by the end panel A and on the other by the partition D¹. Its normal closing position, in the form herein shown, is at the right hand of the tracks G, abutting against the partition D¹. The felting G³ 65 provides a tight closure.

H is an outer track extending between the end panels A and A¹. H¹ is a sliding gate travelling therealong which, when in closing position, closes the compartment between the 70 end panel A¹ and the partition D¹. It may however be positioned in front of either of the other two compartments. The felting strips D³ and H³ provide proper closure or packing, to prevent a circulation of air into 75 or out of the compartment when the gate is in closing position.

Access may be had simultaneously to the two end compartments by sliding the gate H¹ to the left and the gate E¹ to the right. 80 Access may be had simultaneously to the middle compartment and the right compartment by sliding the gates H¹ and G¹ to the limit of their excursion to the left. Simultaneous access may be had to the central and 85 the left hand compartments by sliding the gate E¹ to the right and G¹ to the left, until the center of each gate is opposite the partition D. If the gate H¹ is then moved to the left and aligned with the other two gates, 90 the right compartment is entirely opened and the center and the left hand compartments being half opened, it is possible to have access to all the compartments at once.

It will be realized that whereas I have 95 illustrated a practical and operative device, nevertheless many changes may be made in the size, shape, number and disposition of parts without departing from the spirit of my invention. I wish my description and 100 drawings to be taken, therefore, as in a broad sense diagrammatic or illustrative, rather than as limiting me to the specific showing herein made. In particular it will be realized that whereas I have illustrated a display case which is separated into a plurality of air tight compartments, I do not limit myself to such structure. Obviously my ar- 105

arrangement of gates may be employed with a case which is only partially so divided, or which has no partitions at all.

I claim:

- 5 1. In a display case, end panels and intermediate partitions adapted to divide the case into a plurality of separate compartments, the partitions terminating at their rear edges within the vertical plane bounded by the rear edges of the end panels, a plurality of tracks and sliding gates, each gate being mounted upon and slidable along a separate track, one of said tracks extending from end to end of the case and another of them extending from one end of the case to one of the partitions, the gates being constrained to lie in and slide along the plane of said tracks.
- 10 2. In a display case, end panels and intermediate partitions adapted to divide the case into a plurality of separate compartments, the partitions terminating within the vertical plane bounded by the rear edges of the end panels, a plurality of sliding gate members and means for guiding them, the paths of said gate members being parallel but separate, one of said partitions terminating in such position as to intercept the guiding means for two of said gate members while permitting the passage of a third, and another of said partitions terminating in such position as to permit the passage of all of said gate members.
- 15 3. In a display case, end panels, two intermediate partitions adapted to divide the case into three separate compartments, the partitions terminating within the vertical plane bounded by the rear edges of the end panels, three sliding gate members and separate, parallel tracks therefor, one of said partitions terminating in such position as to intercept the two inner tracks, the other of said partitions terminating in such position as to permit the passage of all three of said gate members.
- 20 4. In a display case, end panels, two intermediate partitions adapted to divide the case into three separate compartments, the partitions terminating within the vertical plane bounded by the rear edges of the end panels, three sliding gate members and separate, parallel tracks therefor, one of said partitions terminating in such position as to intercept the two inner tracks, the other of said partitions terminating in such position as to permit the passage of all three of said gate members.
- 25 5. In a display case, end panels, two intermediate partitions adapted to divide the case into three separate compartments, the partitions terminating within the vertical plane bounded by the rear edges of the end panels, three sliding gate members and separate, parallel tracks therefor, one of said partitions terminating in such position as to intercept the two inner tracks, the other of said partitions terminating in such position as to permit the passage of all three of said gate members.
- 30 6. In a display case, end panels, two intermediate partitions adapted to divide the case into three separate compartments, the partitions terminating within the vertical plane bounded by the rear edges of the end panels, three sliding gate members and separate, parallel tracks therefor, one of said partitions terminating in such position as to intercept the two inner tracks, the other of said partitions terminating in such position as to permit the passage of all three of said gate members.

3. In a display case, end panels, and intermediate partitions adapted to divide the case into a plurality of separate compartments, the partitions terminating within the vertical plane bounded by the rear edges of the end panels, a plurality of sliding gate members and means for guiding them, the paths of said gate members being parallel but separate, one of said partitions terminating in such position as to intercept the guiding means for two of said gate members while permitting the passage of a third, and another of said partitions terminating in such position as to permit the passage of all of said gate members.

4. In a display case, end panels, two intermediate partitions adapted to divide the case into three separate compartments, the partitions terminating within the vertical plane bounded by the rear edges of the end panels, three sliding gate members and separate, parallel tracks therefor, one of said partitions terminating in such position as to intercept the two inner tracks, the other of said partitions terminating in such position as to permit the passage of all three of said gate members.

Signed at Chicago, county of Cook and 60
State of Illinois, this 16th day of June,
1925.

WILLIAM T. SHERER.
